**COLLAPSIBLE BORING HEAD FOR
MINING MACHINE**

Carl A. Wilms, Chicago, Ill., assignor to Goodman Manufacturing Company, Chicago, Ill., a corporation of Illinois

Application December 17, 1953, Serial No. 398,699

11 Claims. (Cl. 262—7)

This invention relates to improvements in mining machines of the boring type wherein one or more rotary boring heads are equipped with a plurality of cutter-carrying arms projecting in a generally radial direction from a hub.

Among the objects of the invention is to provide a boring head structure wherein the arms are capable of swinging from their normal working positions relative to the hub into collapsed positions of greatly reduced working diameter, so as to facilitate withdrawal of the boring head from a previously cut bore, and also facilitate maneuvering of the mining machine in the limited trammimg spaces usually available in mines.

A further object of the invention is to provide a simple and efficient form of control mechanism for effecting uniform movement of the arms between their fully extended working positions and their collapsed positions of reduced diameter.

Other objects and advantages of the invention will appear from time to time as the following description proceeds.

The invention may best be understood by reference to the accompanying drawings, in which:

Figure 1 is a front view of a boring head constructed in accordance with my invention and showing the cutter-carrying arms thereof in fully extended working position;

Figure 2 is a view similar to Figure 1 but showing the cutter-carrying arms in collapsed or contracted position;

Figure 3 is similar to Figure 2 but showing portions of the hub and arms in vertical section;

Figure 4 is an enlarged detail section taken generally on line 4—4 of Figure 3;

Figure 5 is an enlarged detail section taken on line 5—5 of Figure 3;

Figure 6 is a detail section taken on line 6—6 of Figure 5 but drawn to a slightly larger scale.

Referring now to details of the embodiment of the invention shown in the drawings, 10 indicates generally a boring head having a hub 11 with a plurality of arms 12, herein three in number, extending therefrom. The hub is hollow and includes a hollow drive shaft section 13 journaled in a suitable supporting frame 14 forming part of the mining machine. A forwardly projecting tapered lead screw core-breaking member 15 may be fixed as usual on the front of the hub 11 as by means of cap screws 14a.

Each of the arms 12 consists of a hollow base 16 (integral with hub 11) and an elongated end member 17 hinged to said base on a pivot pin 18 so as to be swingable in a plane substantially perpendicular to the axis of rotation of the boring head. Each end member 17 consists of a generally straight inner end portion 19 merging into an outer end portion 20 which is curved on a substantial arc in one direction of rotation of the boring head. The conformation of the arms is such that, when they are in fully extended cutting position as

2

shown in Figure 1, the inner end portions 19 of the arms assume a generally radial relation to the hub, while the outer ends curve outwardly from the hub in the direction of normal rotation of the head, as indicated by 5 the arrow in Figure 1. When the arms 12 are pivoted into collapsed position toward the hub 11, as seen in Figure 2, the pivoted end members 17 are arranged to interfit with each other in nesting relation, so as to reduce the overall diameter of the boring head, as seen by 10 comparison of Figures 1 and 2.

As is usual with boring heads of the kind to which this invention relates, a plurality of cutter-carrying supports is mounted on each of the arms thereof. In the present invention, the outer end portion 20 of each arm 15 has an outermost L-shaped cutter support 23 (Fig. 4) projecting forwardly from the extreme outer end thereof and a second cutter support 24 projecting from the front face of the outer end portion 20 intermediate the first-named cutter support and the pivot pin 18. A third, innermost cutter support 25 may also be provided, in the form shown said cutter support being mounted on the front face of the hub closely adjacent the inner end of each pivoted arm member, as shown in Figures 1 and 4. As is usual with cutter supports of this kind, 25 the forward ends thereof are curved on arcs which are substantially coincident with the kerfs to be cut thereby. A plurality of cutter bits 26, 26 are detachably secured as usual along the front edges of each of said articulated cutter bit supports.

Referring now in greater detail to the construction of the arms 12 and their pivoted mounting on the hub, it will be seen in Figure 4 that each hollow base 16 includes front and rear walls 27 and 28 in which the pivot pin 18 is journaled. The outer ends of the pivot pin 30 are fixed in front and rear cheeks 29 and 30 forming part of the straight inner end portion 19 of the pivoted arm member 17. Said cheeks engage the outer faces of the front and rear walls of base 16, as shown in Figure 4. In the form shown herein, the front end of the pivot pin 18 has a flanged head 31 countersunk in the outer face of the front cheek 29 and secured to said cheek as by one or more bolts 32. The rear end of the pivot pin is keyed as at 35 in the rear cheek 30 and is secured thereto as by a retaining plate 36 and a plurality of bolts 37, 37.

A chain sprocket 38 is fixed as by feathering at 39 to each of the pivot pins 18 between the front and rear walls 27 and 28 of its respective base 16.

Stop means are provided for limiting the hinged movement of each of the pivoted arm members 17 so as to hold the latter in predetermined uniform angular relation to the hub when the cutter head is in fully extended, operating condition. In the form shown herein, the stop means consists of a pair of bearing shoulders 40, 40a, in each case, formed on the hub 11, adjacent the front and rear walls 41 and 42 of the latter, in position to be engaged by stop surfaces 43, 43a formed on the inner ends of the front and rear cheeks 29 and 30 of each pivoted arm member 17 when the latter are in fully extended normal cutting position, as shown in Figure 1.

Means are provided for controlling the hinged movement of the pivoted arms so that they may be moved into collapsed position as shown in Figure 2. In the form shown herein, said control means includes a control shaft 45 extending axially of and rotatably supported in the hollow shaft 13 of the boring head. The control shaft 45 may be provided with any suitable means (not shown) under manual control of the operator, for rotating the control rod in either direction relative to the hollow shaft 13. As seen in Figure 4, the front end of the control shaft has a chain sprocket 48 fixed thereon engaged by a

continuous chain 49 which is trained about each of the chain sprockets 38 fixed on the several pivot pins 18 which, in turn, are fixed to their respective pivoted arm members 17, as previously described. It will thus be seen that, by rotating the control shaft 45 and its chain sprocket 48 relative to the hub 11 and drive shaft 13 in a counterclockwise direction (Fig. 3), all of the pivoted arm members 17 will be simultaneously swung toward collapsed position. Conversely, when it is desired to swing the arms from their collapsed position to their fully extended cutting position, the control shaft 45 is rotated in the opposite direction to restore the arms to the fully extended cutting position shown in Figures 1 and 3.

It will further be understood that the chain 49 should be maintained in reasonably taut condition and, in particular, that it should be adjusted with respect to the three sprockets 38 so that each of the pivoted arm members 17 will reach their fully extended positions simultaneously. If the chain is not properly adjusted relative to the three sprockets to accomplish this purpose, it is possible that one or two of the arms might reach their fully extended position with the bearing shoulders 43, 43a thereon engaging the stop faces 40, 40a on the hub while the corresponding stop means on one or two of the other arms have not yet become mutually engaged. In such case, should the boring head be put into operation, the latter arm or arms would be free to swing a short distance until they engage their cooperating stop faces. This movement, when caused by engagement with the working face, might readily occur with such force as to damage or break the adjusting chain 49.

In order to provide desired relative adjustment of the chain and the chain sprockets 38, I provide a plurality of chain tension adjusting means effective on the chain between each adjacent pair of chain sprockets. One of these adjusting devices shown at the left-hand side of Figure 3 is especially designed to take care of the eight of chain which passes between the uppermost and lowermost sprockets shown in this figure and which also passes over the center sprocket 48. As shown enlarged in Fig. 5, 40 this adjusting device consists of a cross piece 50 having a pair of spaced roller pins 51, 51 carrying rollers 51a, 51a mounted near opposite ends thereof. Said cross piece has a shank 52 with a reduced intermediate portion 53 adapted for endwise sliding fit in a recess 53a formed at the inner end of a bore 54 extending through the hub 11, in radial alignment with the axis of rotation of said hub. Said intermediate guide portion and recess preferably have corresponding irregular guiding surfaces, such as opposed flattened faces 55 and 56, to hold the cross piece against rotation, as shown in Figure 6.

A sleeve 57 is threaded through the bore 54 in hub 11, in the form shown the hub also having an exterior boss 58 integral therewith. Said threaded sleeve is formed with a hexagonal head 59 on its outer end. A stem 60 extends through the sleeve 57 and is connected at its inner end to the shank 52 as by a cross pin 61. The outer end of said stem is threaded to receive a nut 62.

When the adjusting device is in assembled relation, as shown in Figure 5, the threaded sleeve 57 also has a large nut 63 threaded thereon between the head 59 and the outer face of the boss 58 so as to form, in effect, a lock nut for holding the threaded sleeve in various positions of endwise threaded adjustment relative to the wall of the hub through which said sleeve passes.

The adjusting means just described is such as to permit limited inward or outward positioning of the cross piece 50 with its rollers 51a, 51a by first loosening the outermost nut 62 on the outer end of stem 60 and also the larger lock nut 63 on the threaded sleeve 57, and then turning said sleeve inwardly or outwardly to the desired position of readjustment. The sleeve may then be locked in place by tightening the lock nut 63 and the end nut 62.

A somewhat similar form of tension adjusting means is employed to take care of the chain where it passes directly from one chain sprocket 38 to an adjacent

sprocket. Two of such adjusting devices 70 and 71 are shown for the right side of Figure 3. These devices are substantially the same in construction as the adjusting device previously described as located at the left side of Figure 3, excepting that, in place of a cross bar with spaced rollers, a relatively long arcuate shoe 72 is substituted, which shoe is shaped so as to conform substantially with the path of movement of the chain where it is engaged by said shoe.

The arrangement of the adjusting means described above is such that the adjusting devices are capable of independent manipulation as may be necessary to take up any slack in the chain 49 and, at the same time, to insure simultaneous engagement of the stop faces 43, 43a on all the hinged members 17 with the opposed bearing shoulders 40, 40a on the hub 11.

The use and operation of the mechanism is as follows:

By reason of the pivoted mounting of the hinged arm members 17 on their respective bases 16 and the arcuate conformation of the outer ends of said hinged arm members, as shown in Figure 1, said hinged arm members are capable of being collapsed inwardly with their adjacent sides brought into an extremely close-fitting relation to each other, as shown in Figure 2, so as to reduce the overall diameter of the cutter head to a minimum. It will be observed, for instance, that the outermost cutter support 23 at the end of each hinged arm 17 projects tangentially in advance of said arm so that each arm may be folded inwardly toward the hub, with the outermost cutter support overlapping the pivot pin of the next arm and with the inner end portion 19 of each hinged arm nested closely to the outer end portion of the next arm (see Figure 2). When so folded or collapsed, the cutter arm supports 23 and 24 on the several hinged arms also fold together without interference with each other and also without interference with the innermost cutter arm supports 25 on the hub.

In operation, it will be understood that the hinged arm members 17 are normally extended to their maximum diameter for cutting, as shown in Figure 1. When it is desired to withdraw the cutter head from the working face, said cutter head is initially withdrawn a sufficient distance to free the projecting cutter supports 23, 24 and 25 from the individual kerfs which they cut in the working face while making a bore. The control mechanism for operating the chain 49 can then be actuated to swing the hinged end members 17 into the collapsed position shown in Figure 2 so as to permit the cutter head to be readily removed from the bore and also to facilitate the maneuvering of the entire machine as it may be trammed from place to place in the mine.

Although I have shown and described certain embodiments of my invention, it will be understood that I do not wish to be limited to the exact constructions shown and described, but that various changes and modifications may be made without departing from the spirit and scope of the invention as defined in the appended claims.

I claim:

1. In a boring head for mining machines, a hub having a plurality of radially projecting arms with a plurality of cutter-carrying supports projecting forwardly from each of said arms, each of said arms having hinged connection with said hub for inwardly collapsing movement toward the latter in a plane generally perpendicular to the axis thereof, the adjacent sides of said arms and the cutter-carrying supports on said arms being formed for mutually inter-fitting relation with each other for substantially the full length of said arms when in collapsed position.

2. A boring head structure in accordance with claim 1, wherein the inner ends of the hinged arms have stop faces adapted to engage bearing faces on the hub when said arms are swung outwardly to similar cutting positions relative to said hub.

3. A boring head structure in accordance with claim 1,

wherein the outer ends of the hinged arms are curved along arcs approximating that of the overall diameter of the boring head when said arms are in fully collapsed positions.

4. A boring head structure in accordance with claim 1, wherein the hub includes a hollow casing with integral hollow bases projecting radially therefrom, to which each of the hinged arms are pivotally connected, and control means is enclosed in said hollow hub and arms for causing simultaneous hinged movement of said arms relative 10 to their respective bases.

5. A boring head structure in accordance with claim 4, wherein each of the arms is fixed on a pivot pin passing through its respective hollow base, a chain sprocket is fixed on each pivot pin within said hollow base, and an 15 endless chain is trained over all of said chain sprockets and enclosed within said hollow bases and said hub.

6. A boring head structure in accordance with claim 5, wherein means are provided under manual control of the operator for selectively causing movement of said chain 20 in one direction or the other relative to said hub.

7. A boring head structure in accordance with claim 6, wherein the control means includes a shaft rotatably mounted axially of said hub and having a drive sprocket thereon engaged with the chain, and wherein the shaft 25 is rotatable under manual control independently of the rotation of said hub.

8. A boring head structure in accordance with claim 7, wherein the inner ends of the hinged arms have stop faces adapted to engage bearing faces on the hub when said 30 arms are swung outwardly to similar cutting positions relative to said hub, and independently operable chain tensioning devices are mounted on the hub in position

to engage the chain between each adjacent pair of chain sprockets.

9. A boring head structure in accordance with claim 8, wherein the chain tensioning device which engages a bight of chain directly driven by the drive sprocket of the control means includes an adjustable member having spaced bearing members adapted to span the chain sprocket and engage the chain bight at opposite sides of the chain sprocket.

10. In a boring head for mining machines, a hub, a plurality of radially projecting, cutter carrying arms hinged to said hub for inwardly collapsing movement toward said hub in a plane generally perpendicular to the axis of the latter, said hinged arms having cutter carrying supports projecting forwardly therefrom, said hub also having a plurality of fixed radially projecting arms with cutter carrying supports projecting forwardly therefrom, said fixed arms and their cutter carrying supports having radii shorter than the innermost radii of the cutter carrying supports on the hinged arms, all of said arms and their cutter carrying supports being formed for mutually interfitting relation with each other when the hinged arms are in collapsed position.

11. The structure of claim 10, wherein each shorter fixed arm is closely adjacent the inner end of a pivoted arm.
